Application October 19, 1943, Serial No. 506,858

14 Claims. (Cl. 100—31)

1

My invention is a machine designed particularly for tying coils of wire, but capable of ready adaptation for tying other articles.

It is one object of my invention to provide a machine for gripping and holding an article, for example, a coil of wire, and wrapping a length of wire around it and tying together the ends of the wire length.

Another object is to apply pressure to the article so that it will be compacted and so held, during the tying operation.

A further object is to provide such a machine which can be used for tying articles, such as coils of wire, of different sizes, without any change in the machine.

Another object is to provide novel mechanism for handling the tie wire, paper or other materials adaptable for tying, novel knotting means and novel article gripping and holding means.

Still a further object is to provide a machine of such kind that it may be used in batteries for certain kinds of article tying.

With these and other objects in view, my invention consists in the construction, arrangement and combination of the various parts of my tying machine, whereby the objects contemplated are attained, as hereinafter more fully set forth, pointed out in my claims, and illustrated in the accompanying drawings, in which:

Figure 1 is a side elevation of a tying machine illustrative of and embodying my invention.

Figure 2 is a vertical, sectional view of the machine taken on the line 2—2 of Figure 3.

Figure 3 is a horizontal, sectional view taken on the line 3—3 of Figure 2.

Figure 4 is a detail, vertical, sectional view of part of the article gripping device, illustrating the slot for the chain and associated parts.

Figure 5 is a vertical, sectional view of part of the wire cut-off and tying mechanism.

Figure 6 is a top view of the rotary member of the wire tying mechanism; and

Figure 7 is a vertical sectional view of the overrunning clutch structure.

In the drawings herewith, I have shown a frame having upright legs 10, connecting members 11 near the bottoms of the legs and a table 12 to support working parts and provided with suitable opening for working parts.

Resting on the table, and bolted thereto, if desired, is a base 14, provided with suitable openings and bosses. On the base 14 is mounted the article gripping mechanism and the wire handling and tying mechanism, which intimately cooper-

ate. The other operating mechanism is largely below the table.

The device is preferably hydraulically or pneumatically operated, and it could be otherwise mechanically operated. I shall describe it as hydraulically operated.

The machine illustrated in my drawings is shown in a form adapted for tying coils of wire, and will be so described, but it could be very easily adapted for tying other articles, and I do not desire to limit the use of my improvement to the tying of coils of wire.

The base 14 is provided with raised bosses 16 and 18 which may be machined on their top faces without machining the entire base top.

On the boss 16 is a detachable support or bed 17 for a portion of the article to be tied. On the boss 18 is a support 20 for that portion of the coil being tied. This support 20 has a plate-like portion bolted to the boss 18 and having parallel upstanding rib-like portions 22, which are concave on top to fit the coil. Adjacent the portions 22, the plate-like portion 20 is provided with slots 23, in which are pivoted the lower ends of article holding and locking arms 24. These arms 24 have projecting portions 26. When the arms 24 are in their upright article-holding positions shown in Figure 2 and in dotted lines in Figure 1, the portions 26 fit down into the slots 23 and form parts of the supporting rib-like portions 22. The arms 24 can swing to open position, as illustrated in Figure 1, whereupon the portions 26 then project upwardly from the slots 23, as shown in Figure 1.

It will be seen that when the coil 25 is dropped upon the portions 26 in preparation for tying, those portions are forced into the slots 23 and the effect is to swing the arms 24 from open position of Figure 1 to article holding position of Figure 2.

Supported on the boss 18 is a guide 30, which has in one face the channel 32. I provide a suitable vertically, reciprocable article gripper, indicated generally at G (Fig. 1), which has a number of functions. It functions in cooperation with the arms 24 to compact and grip and hold the article to be tied and it carries and guides the chain hereinafter described.

This article gripper G comprises two parallel, immediately adjacent upright bars 34, 36 bolted or otherwise fastened together. They are both secured to an upright slide plate 38, which slides in the channel 32 and is held in place by the overlying face strips 40. On the faces of the members 34, 36 farthest from the plate 32, they

have projecting ribs or flanges 42, 44 to engage the article to be tied and to keep it away from those areas of the faces of the members 34, 36 which lie between the flanges 42, 44. The members 34, 36 have at their upper ends laterally spaced, forwardly projecting arms 46, the under faces of which are concave as at 47 to fit the coil of wire. In the forward part of the member 36 is formed a channel or slot 48 for a roller chain 50, or any device equivalent for the purpose. This chain 50 meshes with a sprocket 52 (Fig. 2) journaled in a suitable slot 54 in the lower part of the member 36. As will be seen from Figure 3, the slot 48 has somewhat of an H-shape to fit the chain. Pivoted to the upper mesh of the chain 50 is a finger 56 which is at the side of the chain. It will, of course, be understood that the slot is so shaped as to permit the travel of this finger.

The finger is pivoted to the top roller pin of the conventional chain. To suitably guide the finger, it has at the opposite side of the slot a link 58 shown in dotted lines in Figure 2, one end of which is mounted on the top pin of the chain, and the other end of which is connected with the finger 56 by a standard pin and roller 60. The slot 48 continues into one of the members 46 as illustrated in Figure 2. The slot 48 terminates in a peculiarly shaped extension 48a better shown in Figure 4. The slot 48a has at the upper part the shoulder 48b, so that when the chain reaches its furthermost position in its travel upwardly and then moves forwardly and then downwardly, the last pin of the chain and the finger 56 slide under the shoulder 48b, which thereupon forms a rigid backing to prevent the finger being pushed upwardly, after it has assumed its final position with relation to the slot extension 48a. By the structure just described the finger 56 is held against being pushed up during the final tying operation. The finger 56 has in its free end and extending along one face, the wire receiving groove 62, which will be again referred to.

The sprocket 52 is mounted on and carried by the gripping device G (Fig. 2). When the sprocket 52 rotates it functions to move the chain 50 lengthwise in its guide slot. The sprocket 52 is fixed on a shaft 64, which is suitably journaled on the members 34, 36 and carries at one end a pinion 66. A bracket 68 has a flange 70 secured to the lower end of the gripping device G. On the bracket 68 is journaled a shaft 71 on which is a gear 72 meshing with the pinion 66. Fixed to the shaft 71 is an operating arm 74, which projects in both directions from the shaft. At one end it is pivoted as at 76 to the piston rod 78, which in turn is connected to a piston, not shown, in a cylinder 80, which is pivoted at its lower end on the bracket 68. The arm 74 is rocked by the piston rod 78 and is provided with set screws 82, 84 which may be adjusted to cooperate with a stop 86, whereby the stroke of the arm may be regulated to a degree. Thus it appears that the chain 50 is actuated lengthwise in both directions by means of the piston in the cylinder 80, and the gearing means whereby the motion of the piston is transmitted to the sprocket 52.

The movement of the chain downwardly is limited by means of a stop 88 carried on an arm 90 extending from the plate-like member 20. The stop 88 coacts with a lug 92 formed on the finger 56. In the member 36 at an appropriate distance above the sprocket 52 is a fore-and-aft hole 94

in which is an adjustable bushing 96, the outer end of which has a tapered mouth 98 to receive the end of the tie wire as hereinafter more fully explained.

5 Connected to the lower end of the article gripping device G is a piston rod 100 (Fig. 2), which in turn is connected with a piston, not shown, in a cylinder 102 (Fig. 1).

On the outer side face of each member 46 is 10 a rabbet 104. In the rabbet spaced from the rear wall thereof is a guide flange 106 tapered as at 108 to facilitate the entrance of the upper end of the arm 24. The guide flange 106 carries an anti-friction roller 110 to coat with the arm 24.

15 Thus after the arm 24 has been raised to its dotted line position of Figure 1, by putting a load on the member 26, then when the member G is lowered, the upper end of the arm 24 will enter the rabbet 104, being guided, if necessary by the bevel face 108 of the guide flange 106, and as the gripper member G is lowered, the front end of each member 46 will travel downwardly lengthwise of its appropriate arm 24 with that arm between the anti-friction roller 110 and the shoulder of the rabbet 104.

20 *Wire feeding, cut-off and tying mechanism*

Supported on the frame of the machine are 25 laterally spaced guide rods 112 (Figs. 2, 3, 5 and 6). On the guide rods 112 is mounted the slide- 30 able bracket 114, which supports the cut-off and tying head H. The cut-off and tying head H comprises a block 116 supported on the arm 118 of the bracket 114. In the upper end of the block 116 and extending through it from front to rear is a suitable bearing bushing 120, in which 35 is a rotatable, cylindrical-shaped member 122. One end of the rotating member 122 projects rearwardly beyond the block 116 and has the flange 123, which is provided with a slot 124 40 extending diametrically across it. The other end of the rotating member 122 projects forwardly beyond the block 116 and on this projecting end is mounted a sprocket 126 having an over-running clutch connection with the member 122. Extending diametrically through the rotating member 122 near the flange 123 and aligned with the slot 124 is a bore 128. Extending lengthwise 45 through the rotating member 122 is a bore 130. The block 116 has a hole below the rear end of the rotating member 122 and the bushing 120, as indicated at 132 in Figure 5. The bushing 120 has a registering hole 134. Directly above the holes 132 and 134 the bushing has a registering hole 136 and the top of the block 116 has a hole 138. Slidable in the bore 128 in the rotating member 122 is a cut-off plunger 140, the 50 length of which is just slightly less than the diameter of the rotating member 122. The plunger 140 in its operation sometimes slides partly out of the bore 128 in the rotating member 122 but when it is wholly received in that bore, it 55 will be observed that the member 122 may rotate in the bushing 120 and that the plunger 140 will then travel with it.

60 The plunger 140 has a rearwardly projecting lug 142, which projects into the slot 124 and functions to bend the wire in the manner hereinafter described. The front face of the plunger 140 is flattened as at 146 for the reason which 65 will be shortly explained.

In the bore 130 in the rotating member 122 is a hardened bushing 148, the front end of which projects into the bore 128 as illustrated in Figure 6. The lower end of the plunger 140 has

a slot 150, as shown in Figure 5, the purpose of which will be explained. The forward part of the bore 130 is threaded and receives an adjustable screw 152. The rearward end of the bushing 148 serves as a cut-off member. The 5 bushing 148 fits snugly in place and as it wears, it may be forced rearwardly by means of the adjustable screw 152.

The sprocket 126 is held against lengthwise movement on the rotating member 122 by a 10 shoulder 154 thereon and by a washer 156 and a nut 157 on the screw 152. The sprocket 126 has an over-running clutch connection with the rotating member 122, that structure being indicated at 158 and being of any suitable known kind. In Figure 7, I have shown a sectional view illustrating in detail one form in which this over-running clutch might be embodied. As shown the casing or outer sleeve 158a forming part of this over-running clutch is formed as part of the sprocket 126. In that portion of the shaft 122, which is received in the sleeve body 158a are formed notches 158b, each of which receives a roller 158c. The notches are of such shape that when the sleeve 158a rotates counter-clockwise with relation to the shaft 122, as the parts are viewed in Figure 7, the rollers are in the deeper parts of the notches, and the shaft 122 is not actuated. On the other hand, when the sleeve 158a travels clockwise, the rollers move into the narrow or shallow parts of the notches 158b, and thereby lock the sleeve 158a to the 25 shaft 122, causing the shaft to rotate with the sleeve. The bushing 148 and the screw 152 have central registering lengthwise holes 160 and 162. In the bore 132 is a plunger 164, which is yieldingly biased upwardly by means of a spring 165 to normally cause the plunger 164 to project across the joint between the rotating member 122 and the bushing 120. Thus the plunger 164 30 functions to lock the rotating member 122 against rotation, so long as the plunger 164 is in its upper position.

Above the cut-off plunger 140 is supported a plunger 166 having above the block 116 a head 45 167. Any suitable means may be provided for limiting the movement of the plunger 166 to the desired stroke. The parts are so proportioned that when the plunger 166 is shoved downwardly, until the head 167 engages the block 50 116, the cut-off plunger 140 will be just properly located in the rotating member 122. This movement of the cut-off plunger 140 pushes the plunger 164 down to where that plunger no longer serves to hold the rotary member 122 against rotation. On the rear face of the block 116 is mounted a plate 168, which receives and covers the lower half of the flange 123 as shown in Figure 5. This plate has a boss 170 against which the coil of wire 25 may rub, and whereby any friction caused thereby will be reduced to a minimum. The top of the plate 168 has a groove 172 which registers with the hole 160.

Pivoted to the bracket 114 is a lever 174, which projects forwardly as shown in Figure 2. Pivoted to the lever 174 as at 176 is a piston rod 178 connected in turn with a piston, not shown, in a cylinder 180. On the bracket arm 118 is an 65 upwardly bracket 182 (Fig. 2). In the upper end of the bracket 182 is journaled a shaft 184. On the shaft 184 in a slot 186 in the bracket 182 is a wire feeding roll 188. On the shaft 184 at the side of the bracket 182 is a sprocket 190 (Fig. 2). This sprocket 190 is mounted on the shaft 184 by means of an over-running clutch 70 124 and slot 172 (Figs. 1, 2, 5 and 6), thence

of any standard construction. Mounted in the upper part of the bracket 182 above the roll 188 is a shaft 192, which has an eccentric on which is mounted the cooperating wire feeding roll 194. The shaft is biased toward position for presenting the wheel 194 against the wheel 188 by means of an arm 196 and a spring 197 connected to a flange 198 at the lower end of the block 116.

Extending downwardly from the arm 118 is a bracket 200 which suitably supports a sprocket 202 by any ordinary chain tightening mechanism 202a. The sprocket 202 aligns with the sprocket 126. A chain 204 travels on the sprockets 202 and 126.

Connected with the chain 204 is the upper end of a piston rod 208, which is in turn connected with a piston, not shown, in a cylinder 210 illustrated in Figure 1.

Connected to the bracket 200 near its lower end is a coil spring 212, which is in turn connected to a chain 214, which is trained over the sprocket 190 and then over an idler sprocket 216 on the arm 118 and is then fastened to the forward end of the lever 174.

Hydraulic connections

At 218 is a supply pipe, for instance, for oil under pressure. At 220 is indicated a control valve for controlling flow from the pipe 218, for 30 the purpose of maintaining pressure on one side or the other of the operating mechanism of my machine.

The valve 220 is normally held in one position by means of a spring 222 and can be adjusted to another position by the foot treadle 224. The valve 220 controls the pistons in cylinders 80 and 102 and one side of the piston in the cylinder 180. On the bracket 68 is carried a valve 226 (Fig. 1) which controls the piston in the cylinder 210 and the upward movement of the piston in the cylinder 180. The valve 220 is connected with the top of the cylinder 102 by a pipe 228. The pipe 228 is connected by the extension flexible pipe 230 with the foot of the cylinder 80. A pipe 232 and flexible extension 234 connects the supply pipe 218 with the valve 226. The valve 226 is connected by a pipe 236 and flexible pipe 240 with the lower end of the cylinder 180 and by branch flexible tube 242 with the top of the cylinder 210.

Perhaps it should be here mentioned that in starting the operation, a valve, not shown, is opened in the line 218, so as to supply oil to the machine under pressure and the pipe 232 then remains under pressure, so long as the machine is being operated.

The valve 220 is connected by a pipe 244 with the lower end of the cylinder 102 and by a branch pipe 246 and a flexible tube 248 with the upper end of the cylinder 180, and by an extension pipe 250 and flexible tube 252 with the top of the cylinder 80. The valve 226 is connected by pipe and tube connections 254 with the lower end of the cylinder 210.

Practical operation

I will now describe the sequence of operation of my improved tying machine. In describing the operation, it will be necessary to complete the description of some of the parts.

The tie wire 252 is fed from any suitable roll as a source of supply between the wire feeding rolls 188-194 through the screw 152 and bushing 148, and through the slot 150 and the slot 75 124 and slot 172 (Figs. 1, 2, 5 and 6), thence

along slot 153 in the top of the plate-like member 20 (Fig. 3), and into the mouth of the bushing 96. This bushing is perhaps best shown in Figure 2, but is shown in position for the threading operation mentioned in Figure 1.

At this time the gripping element G is in its raised position of Figure 1 and the finger 56 on the upper end of the chain 50 is just below the wire as shown in Figure 1. The arms 24 are then in their position shown in full lines in Figure 1.

A coil of wire 25 is dropped on the supports 17-22, thereby depressing the portions 26 of the arms 24 and moving the arms 24 from their full line position of Figure 1 to their upright dotted position of that figure, so that their upper ends will enter the rabbets 104 as the article gripping member G is lowered.

A valve, not shown, is opened for admitting pressure to the supply pipe 218. The pedal 224 is depressed against the action of the spring 222 to a position which allows the pressure fluid to travel from the pipe 218 through the valve 220 to the pipe 228. The pressure fluid enters the upper end of the cylinder 182, forcing the piston therein downwardly and thereby lowering the piston rod 180 and the article gripping member G. It is obvious that there is considerable load on the piston rod 180, and the first important motion of the machine is the downward movement of the element G until it contacts the article to be tied.

The bracket 68 and cylinder 80 travel downwardly with the article gripping element G and, when the pressure builds up to a certain point, the fluid by-passing the cylinder 182 and traveling through the flexible tube 230 enters the lower part of the cylinder 80 and moves its piston and piston rod 78 upwardly, thereby rocking the arm 74 to its position shown in Figure 2. The effect of the rocking of the arm 74 is to rotate the shaft 71 and the gear 72 carried thereby for actuating the gear 66 and shaft 64 and sprocket 52 to cause the chain 50 to travel from its position shown in Figure 1 to its position shown in Figure 2. The last part of the movement of the chain serves to move what is then the upper part of the finger 56 into the enlarged portion 48a of the slot 48, and to position where the upper end of the finger 56 is backed by the shoulder 48b, Figures 2 and 4.

During this downward movement of G, the members 46 slide over the upper ends of the arms 24 (see Fig. 2). Just before the beginning of the upward movement of the finger 56, the tip end of the tie wire 252 overlies the finger 56 and projects into the beveled end of the sleeve 96, as shown in dotted lines in Figure 1. As the finger 56 travels upwardly, the end of the wire 252 enters the shallow slot 62 in the end of the finger 56. A little further upward travel of the finger 56 bends the wire so as to form its end into a hook, which continues to travel in a suitable groove 260 (Fig. 3) formed in the channel 48. The hook on the end of the wire 252 is indicated at 262 in Figure 2. This hook is utilized in the final tying operation, as explained below.

It will be seen that the lowering of the article gripping element G serves to grip the wire coil 25 on the members 22 and between the arms 24 and the parts of the gripping member G, so as to snugly engage and compact the coil of wire and to hold it compacted during the tying operation.

Pivoted on the bracket 68 at 264 between its

ends, is a lever 265 (Fig. 1). One end of this lever is operatively connected with the valve 226 and the other end projects into the paths of two spaced striker rollers 266 and 268 mounted on the gear 72. The final upward movement of the piston rod 18 and rotation of the gear 72 thereby, which has already been explained, causes the striker roller 268 to engage and move the lever 265 sufficiently to actuate the valve 226 to its position where it permits flow from the pipe

218 and pipe 232 and tube 234, through such valve and through the piping 236-240, to the bottom of the cylinder 180 and through the piping 236-242 to the top of the cylinder 210. When pressure is thus supplied to the lower end of the cylinder 180, the piston in that cylinder forces the piston rod 178 upwardly. The upward movement of the piston rod 178 raises the pivoted lever 174 until that lever strikes the stop screw 270 adjustably mounted on the bracket arm 118.

The effect of this first and limited upward movement of the lever arm 174 is to permit the spring 212 of Figure 2 to pull the chain 214 for a limited distance, thereby rotating the sprocket 190 and shaft 184. However, the wire feeding wheel is not rotated correspondingly because of its over-running clutch connection (of any standard form not shown) with the shaft 184.

After the lever 174 strikes the stop pin 270, the further upward movement of the piston rod 178 moves the entire bracket 114 and the cut-off and tying head H upwardly until the head 167 of the plunger 166 strikes the underside of one of the members 46, as at 272 (Fig. 2). Such undersurface forms an anvil and the plunger 166 is forced downwardly relative to the head H. This downward movement of the plunger 166 has several results. First, the plunger 140 is forced downwardly until the wire 252 is engaged at the upper end of the slot 150 and cut off by the plunger 140, cooperating with the end of the hardened sleeve 148, which projects into the bore 128. The parts are so arranged that there is a slight further movement of the plunger 140 after the wire has been cut, and in this slight further movement, the top of the slot 150 and the projecting lug 142 serve to force the wire downward into the slot 124, thus bending the end of the piece which has been cut off.

In the meanwhile the lowering of the gripping member G has brought the hook-like part 262, formed by the finger 56 in the opposite end of the tie wire, down into the slot 124, where it is right alongside the bent portion just described.

I will now describe the twisting or tying operation proper. At the same time fluid was permitted to flow from the valve 226 to the bottom of the cylinder 180, it was likewise permitted to flow through the branch piping 242 to the top of the cylinder 210. The piston rod 208 extending from that cylinder being tied to the chain 204 tends to rotate the sprocket 126 and the rotary cylindrical member 122, but could not do so because of the projection of the plunger 164 into the bore 128.

When, however, the plunger 166 was lowered in the manner hereinabove described, the effect was to move the plunger 164 out of the bore 128 and to move the upper end of the plunger 140 into the bore 128, whereupon the cylindrical member 122 might rotate within the journal 120. The pressure in the cylinder 210 functions to further actuate the piston rod 208 and the chain 204 and sprocket 126 for imparting to the rotatable cyl-

inder 122 three full rotations. This has the effect of twisting together the ends of the tie wire in the slot 124 and thus tying the tie wire around the coil 25.

The operator then releases the foot pedal 224 so that the valve 220 is actuated to position where pressure from the supply line 218 travels into the pipe 244 to the bottom of cylinder 102. The pressure in the lower end of cylinder 102 raises the piston therein, thereby raising the piston rod 100 and the article gripping element G from its position shown in Figure 2 back to its original position of Figure 1.

Fluid also passes from the pipe 244 to the pipe 250 and flexible tube 252 to the upper end of the cylinder 80, and the piston in that cylinder traveling downward, carries with it the piston rod 78 and rocks the arm 74, thereby rotating the gear 72 and pinion 66 and shaft 64 for rotating the sprocket 52 for moving the chain 59 from its position shown in Figure 2 to its position shown in Figure 1.

It will be obvious that fluid from the pipe 244 also travels through the pipe 246 and tube 248 to the cylinder 180. This places pressure on both sides of the piston preventing any further movement until roller 266 contacts lever 265 which actuates valve 226 which releases the pressure on bottom side of cylinder 180 allowing the piston in cylinder 180 to move downwardly, carrying with it the lever 174 and bracket arm 118. This effects the lowering of the head H, bracket 114, arm 118 and the parts supported by it including feed rolls 188, 194, and chain 214 and cylinder 210.

When the arm 118 starts down, the spring 212 holds the lever 174 snugly against the stop 270 until the bracket 114 strikes the stops 114a on the guide pins 112. Then the wire 252 is in proper alignment with groove 153 in plate 28. The bracket 114 and arm 118 can go no farther but the lever 174 is swung down on its pivot from its position engaging the stop 270 to its full line position of Figure 2. In this latter movement the lever operates the chain 214 causing the chain to rotate the sprocket 190 against the tension of the spring 212. The effect is to rotate the wire advancing roll 188. The wire 252 is held snugly against that roll by the roll 194 and the spring 197. The rotation of the roll 188 moves the wire for re-threading it through the slot 153 (Fig. 3) and into its position shown in Figure 1, where it is free and projects into the sleeve 96. It will be understood that suitable play in the parts is provided for permitting such operations.

The rotation of the gear 72 for moving the chain 59, as above described, also brings the roller 266 into engagement with the lever 265 for operating the valve 226 to position where flow of pressure fluid is permitted to the pipe 254 and the bottom of the cylinder 210, whereupon the piston in the cylinder 210 is moved upwardly. Its piston actuates the chain 208, but the overrunning clutch connection of the sprocket 126 with the rotatable member 122 permits the chain and sprocket to operate without any effect on the member 122. The parts however are restored to position for another wire tying operation.

The operator removes the tied coil 25 and either turns it around so that it can be tied at another place or replaces it with another coil, and when that is done, he releases the lever 224 for another cycle of tying operations.

Summarizing this cycle of operations, the placing of the article to be tied raises the arms 24.

The pedal is operated and head G is lowered for gripping and compacting the article. If the article be a box, for example, the parts are arranged to fit that box and the compacting operation may be eliminated.

When the head G is lowered, the mechanism actuates the chain 50 for bending the end of the tie wire and carrying that end from its position shown in Figure 1 to its position shown in Figure 2. This movement of course pulls more wire from the unshown coil, which is the source of supply. Then the head H is raised, the head 167 striking the anvil 272 (Fig. 2), whereupon the wire is cut off, and the parts adjusted to position where the member 122 rotates for twisting together ends of that piece of wire which has just been cut off from the main supply.

Next the operator releases the pedal 224 whereupon the head G is raised, the chain 50 is moved back from its position shown in Figure 2 to its position shown in Figure 1. The wire feeding cut-off and tying mechanism is lowered, the wire is re-threaded and the piston in cylinder 210 is moved back to its original position.

All the parts are then ready for another operation and a new article is placed in tying position, and the pedal 224 is depressed.

The size of the package determines the length of the stroke of the head G and thereby determines the travel of the chain 50 and the amount of wire supplied by it for each tie, and also determines the length of travel of the wire feeding, tying and cutting mechanism, so that the proper length of wire is supplied by it.

It will be understood that the valves 220 and 226 have the usual exhaust pipe connections 400 and 402 leading to a conventional tank, not shown, connected to a pump, not shown, for putting the oil back into the working line under pressure.

It will be obvious from the description that there are numerous advantages in the structure here shown other than those which have been specifically mentioned. It will also be obvious that numerous changes may be made in the details of the structure of the machine, and it is my purpose to cover by my claims any modifications in form and detail which may be reasonably included within their scope.

I claim:

1. In a tying machine, means for engaging and tightly gripping an article to be tied, a member mounted for actuation to article-holding position in interlocking engagement with the first means by the article to be tied, means for placing a length of tie wire around the article, means for cutting such length from a source of wire supply, and means for tying together the ends of the tie wire.

2. In a tying machine, means for engaging and tightly gripping an article to be tied, said means including a support, a slidale element adapted to form a side and top of the means, a pivoted member having a part adapted to be engaged by an article when placed in position to be tied,

for movement to article-holding position, said element being adapted to receive and hold an end of said pivoted member, means for placing a length of tie wire around the article, means for cutting such length from a source of wire supply, and means for tying together the ends of the tie wire.

3. In a tying machine, an article support, an article engaging element for cooperation therewith, mounted for movement toward and from article-engaging position, means for feeding a

tie wire through said element, said means including a chain having a pivoted finger, said element having a curved channel for the chain to travel in, terminating near one end in a portion with an off-set shoulder to form a backing for the finger, and means for tying the ends of the wire together.

4. In a tying machine, an article support, an article engaging element for cooperation therewith, mounted for movement toward and from article-engaging position, means for feeding a tie wire through said element, said means including a chain having a pivoted finger, said element having a curved channel for the chain to travel in, terminating near one end in a portion with an off-set shoulder to form a backing for the finger, means for reciprocating the element, for carrying the chain with it, means for actuating and moving the chain with relation to the element, and means for tying the ends of the wire together.

5. In a tying machine, means for supporting an article to be tied, a reciprocating article gripping element, means for moving said element to and from position for engaging an article on said supporting means, means for wrapping a length of tie wire around an article gripped by said element, a sliding cut-off and tying head, means for moving said head to and from position to cooperate with said element in any position the said element may have assumed in gripping an article, said head having means for cutting the wire to tying length, and means for tying the free ends of such length together.

6. In a tying machine, means for supporting an article to be tied, a reciprocating article gripping element, means for moving said element to and from position for engaging an article on said supporting means, means for wrapping a length of tie wire around an article gripped by said element, a sliding cut-off and tying head, means for moving said head to and from position to cooperate with said element in any position the said element may have assumed in gripping an article, said head having means actuated by engagement with said element for cutting the wire to tying length, and means for tying the free ends of such length together.

7. In a tying machine, means for supporting an article to be tied, a reciprocating article gripping element, means for moving said element to and from position for engaging an article on said supporting means, means for wrapping a length of tie wire around an article gripped by said element, a sliding cut-off and tying head, means for moving said head to and from position to cooperate with said element in any position the said element may have assumed in gripping an article, said head having cut-off and tying means, including a rotary member with a lengthwise bore through it to receive wire, a diametrical slot at one end for receiving the ends to be twisted together, and a diametrical bore parallel with the said slot for receiving cut-off means.

8. In a tying machine, means for supporting an article to be tied, a reciprocating article gripping element, means for moving said element to and from position for engaging an article on said supporting means, means for wrapping a length of tie wire around an article gripped by said element, a sliding cut-off and tying head, means for moving said head to and from position to cooperate with said element in any position the said element may have assumed in gripping an article, said head having cut-off and tying means, in-

cluding a rotary member with a lengthwise bore through it to receive wire, a diametrical slot at one end for receiving the ends to be twisted together, and a diametrical bore parallel with the said slot for receiving a sliding cut-off plunger and means normally biased to one limit of movement, for engaging the article engaging element and being given cut off movement, when the head is slid to position therefor.

9. In a tying machine, means for supporting an article to be tied, a reciprocating article gripping element, means for moving said element to and from position for engaging an article on said supporting means, means for wrapping a length of tie wire around an article gripped by said element, a sliding cut-off and tying head, means including a device carried by the article gripping element for moving said head to and from position to cooperate with said element in any position the said element may have assumed in gripping an article, said head having means for cutting the wire to tying length and means for tying the free ends of such length together.

10. In a tying machine, means for supporting an article to be tied, a reciprocating article gripping element, means for moving said element to and from position for engaging an article on said supporting means, means for wrapping a length of tie wire around an article gripped by said element, a sliding cut-off and tying head, means including means actuated upon movement of the article gripping element for moving said head to and from position to cooperate with said element in any position the said element may have assumed in gripping an article, said head having means for cutting the wire to tying length and means for tying the free ends of such length together.

11. In a tying machine, means for supporting an article to be tied, a reciprocating article gripping element, means for moving said element to and from position for engaging an article on said supporting means, means for wrapping a length of tie wire around an article gripped by said element, a sliding cut-off and tying head, means for moving said head to and from position to cooperate with said element in any position the said element may have assumed in gripping an article, said head having means for cutting the wire to tying length, means for tying the free ends of such length together, and synchronized means for advancing wire from a source of supply to position for the performance of another cycle of operations by the machine.

12. In a tying machine, means for supporting an article to be tied, a reciprocating article gripping element, means for moving said element to and from position for engaging an article on said supporting means, means for wrapping a length of tie wire around an article gripped by said element, a sliding cut-off and tying head, means for moving said head to and from position to cooperate with said element in any position the said element may have assumed in gripping an article, said head having means for cutting the wire to tying length, means for tying the free ends of such length together, and means actuated by the movement of the head away from the article gripping element, for feeding a supply of wire to position for the performance of another cycle of operations by the machine.

13. In a tying machine, means for supporting an article to be tied, a reciprocating article gripping element, means for moving said element to and from different positions for engaging an

article on said supporting means, mechanisms for supplying a length of tie wire around the article gripped by the element, and means whereby the degree of movement of said mechanisms, and consequently the length of tie wire supplied, is determined by the gripping position of the element.

14. In a tying machine, means for supporting an article to be tied, a reciprocating article gripping element, means for moving said element from an initial position to variable positions for engaging an article on said supporting means, means including an element carried by the article gripping element for feeding a tie wire to varying tying positions depending on the position assumed by the article gripping element when in

5

article gripping position and for bringing the ends of the tie wire together when the element is in article-holding position, and means for tying the ends of the tie wire together.

JOSEPH L. POJMAN.
